UNITED STATES PATENT OFFICE.

EINAR G. HALLQUIST, OF EDWARDSVILLE, ILLINOIS, ASSIGNOR TO COMMONWEALTH STEEL COMPANY, OF ST. LOUIS, MISSOURI, A CORPORATION OF MISSOURI.

RAILWAY TRUCK.

Application filed August 26, 1924. Serial No. 734,197.

To all whom it may concern:

Be it known that I, EINAR G. HALLQUIST, citizen of the United States, residing at Edwardsville, Illinois, have invented a certain new and useful Improvement in Railway Trucks, of which the following is a specification, such as will enable others skilled in the art to which it appertains to make and use the same.

10 My invention relates to railway rolling stock and consists in an improved truck construction.

15 My invention is particularly adapted for use in engine trucks of the type which carry the locomotive body through rockers or other supporting elements which must be mounted on the truck below the level of the top thereof in order to lower the point of support.

20 The object of my invention is to provide a transom and truck frame construction of light weight yet possessing the strength necessary to take care of the load carried as required by the type of body supports referred to.

25 In the accompanying drawings which illustrate a preferred embodiment of my invention, I show a four wheel engine truck having an integral one piece frame, including wheel pieces, pedestals, transoms, and rocker supporting members, and in these drawings—

Figure 1 is a vertical longitudinal section through the center of a truck.

30 Figure 2 is a vertical transverse section on line 2—2 of Figure 1 and is drawn on a larger scale.

35 Figure 3 is a vertical transverse section on line 3—3 of Figure 1 and is drawn on the same scale as Figure 2.

40 The truck is equipped with the usual wheels 1 and axles 2. It will be understood that the axle journals are provided with journal boxes, not shown, upon which rest the equalizers 3 which carry springs 4 upon which are mounted wheel pieces 5 of the truck frame.

45 Wheel pieces 5 are connected at spaced points by transoms, each of which consists in a vertically disposed body wall 7, the top of which is substantially on the level of the top of wheel pieces 5, although an upward projection 8 of limited length may be provided, if desired. The top of the transom is 50 provided with a reinforcing flange 9 extend-

ing outwardly and united with wheel pieces 5.

The ends of the transoms are of the same depth as the wheel pieces but intermediate the wheel pieces they extend substantially below the level of the wheel pieces and are provided with inwardly extending flanges 10 which are united to form a rocker supporting shelf extending substantially the full distance between the wheel pieces. The ends 60 of this shelf between the transoms are connected with the bottom of the wheel pieces by vertical walls 11 and these walls may be reinforced by suitable ribs 12. The depth of these ribs 12 is limited because of the space 70 requirement of the body supporting rockers 13 mounted upon shelf 10.

Due to the space requirements of rockers 13 and the resulting connection between the ends of shelf 10 and the wheel pieces there 75 is a tendency for the frame to fail at the junction of the shelf and walls or of the walls and wheel pieces. To resist this tendency, I provide transom body walls 7 with reinforcing flanges 14 located on the outside 80 thereof and extending from points near the center of the transoms upwardly and outwardly to the wheel pieces with which the ends of the flanges 14 are united. Preferably the outer edge of each flange 14 is provided 85 with a reentrant rib 15 which merges with wheel pieces 5 and also merges with the outer edge of the corresponding flange 9, and ribs 15 may be shaped as indicated at 16 in Figure 3 so as to distribute some of the stresses 90 applied to the flanges 14 to the upper portion of the transom.

Obviously the flanges 14, inclined and positioned as shown, are better adapted to resist the strains in the transoms produced by the load thereon than the horizontal and vertical members 10 and 11. By placing the flanges 14 on the outside of the transoms the space between the transoms is unobstructed for the mounting and tilting of rockers 13 100 or other supporting elements which may be provided for the locomotive body 17.

While I have shown my invention as applied to a four wheel locomotive truck adapted for particular body supporting elements, 105 it is obvious that my invention may be applied to other truck construction with suitable modifications in the details thereof without departing from the spirit thereof as claimed.

I claim:

1. In a railway truck transom, deeper at its center than at its ends, a horizontal load carrying flange, and an inclined reinforcing flange extending from a point on said transom intermediate the ends of said horizontal flange toward the end of the transom.
2. In a railway truck transom, deeper at its center than at its ends, a horizontal load carrying flange near the bottom of the transom, and inclined flanges extending upwardly and outwardly from a point on said transom intermediate the ends of said horizontal flange.
3. In a railway truck transom, a load carrying flange extending from near the center of said transom disposed independently of the line of strain in the transom produced by the load, and a reinforcing flange extending from near the center of said transom disposed along said line of strain.
4. In a railway truck transom having a vertically disposed body wall, a load carrying flange on one side of said wall disposed independently of the line of strain in the transom produced by the load, and a reinforcing flange on the other side of said wall disposed along said line of strain.
5. In a railway truck transom, a vertically disposed body wall, a horizontal load carrying flange on one side of said wall near the bottom thereof, a horizontal flange on the other side of said wall near the top thereof, inclined flanges on the latter side of said wall extending upwardly and outwardly from near the center of the transom, and a return rib on the edge of said inclined flange united with said top flange near the ends thereof.
6. In a railway truck, an integral frame comprising wheel pieces, a transom connecting said wheel pieces and extending below the level of the same, a horizontal flange on one side of said transom and below the level of said wheel pieces, and an inclined flange on the other side of said transom extending inwardly and downwardly from each of said wheel pieces.
7. In a railway truck, an integral frame comprising wheel pieces, a transom connecting said wheel pieces and extending below the level of the same, a horizontal flange on one side of said transom and below the level of said wheel pieces, and an inclined flange on the other side of said transom extending inwardly and downwardly from each of said wheel pieces and provided with a reentrant rib paralleling said transom and united with said wheel pieces.
8. In a railway truck, an integral frame comprising wheel pieces, a transom connecting said wheel pieces and extending below the level of the same, a horizontal flange on one side of said transom and below the level of said wheel pieces, and an inclined flange on the other side of said transom extending inwardly and downwardly from each of said wheel pieces and provided with a reentrant rib varying in depth and deepest near said wheel pieces and united therewith.
9. In a railway truck, an integral frame comprising wheel pieces, a vertically disposed transom connecting said wheel pieces, a load carrying flange on one side of said transom disposed independently of the line of strain in the transom produced by the load, and a reinforcing flange on the opposite side of said transom disposed along said line of strain.
10. In a railway truck, wheel pieces, a transom connecting said wheel pieces and extending below the level of the same, body supporting members carried by said transom near its ends and below said level, and transom reinforcing elements extending from said wheel pieces downwardly and inwardly toward points intermediate the points where said members are carried.
11. In a railway truck, wheel pieces, a transom connecting said wheel pieces and extending below the level of the same, a flange on said transom extending horizontally substantially the full distance between said wheel pieces and adapted to carry body supporting members, and a flange on said transom extending from said wheel pieces downwardly and inwardly along said transom.
12. In a railway truck, wheel pieces, a vertically disposed transom, a rocker supporting flange on said transom below the level of said wheel pieces, rockers mounted thereon, a transom reinforcing member extending downwardly and inwardly from said wheel pieces past said rockers.
13. In a one piece railway truck frame, wheel pieces, spaced transoms connecting said wheel pieces and extending a substantial distance below the level of said wheel pieces, a horizontal shelf connecting the bottoms of said transoms and extending substantially the full distance between said wheel pieces to provide a rocker mounting surface, and reinforcing flanges on the exterior faces of said transoms extending from abreast the central portion of said shelf upwardly and outwardly to said wheel pieces.
14. In a one piece railway truck frame, wheel pieces, spaced transoms connecting said wheel pieces and extending a substantial distance below the level of said wheel pieces, a horizontal shelf connecting the bottoms of said transoms and extending substantially the full distance between said wheel pieces to provide a rocker mounting surface, reinforcing flanges on the exterior faces of said transoms extending from abreast the central portion of said shelf upwardly and outwardly to said wheel pieces.

pieces, and reentrant ribs on said flanges united with said wheel pieces.

15. In a one piece railway truck frame, wheel pieces, spaced transoms connecting 5 said wheel pieces and extending a substantial distance below the level of said wheel pieces, a horizontal shelf connecting the bottom of said transoms and extending substantially the full distance between said 10 wheel pieces to provide a rocker mounting surface, reinforcing flanges on the exterior faces of said transoms extending from abreast the central portion of said shelf upwardly and outwardly to said wheel 15 pieces, reentrant ribs on said flanges united with said wheel pieces, and an outwardly extending horizontal flange on the top of

said transoms united with said wheel pieces and ribs.

16. In a railway truck transom, a load 20 carrying flange disposed independently of the lines of strain in the transom produced by the load, and reinforcing flanges disposed along said lines of strain and converging near the center of the transom. 25

17. In a railway truck transom having a vertically disposed body wall, a load carrying flange on one side of said wall, and a reinforcing flange on the other side of said wall disposed at an angle to said load carrying flange. 30

In testimony whereof I hereunto affix my signature this 18th day of August, 1924.

EINAR G. HALLQUIST.
